CLOCK-SPRING SUPPORT.

Application filed January 20, 1926. Serial No. 82,389.

This invention relates to improvements in casings for supporting and containing clock springs, being particularly directed to barrels or casings enclosing springs for forming the actuating or driving mechanism for 5 clocks. In the present type of so-called eight day clock, the driving spring usually is positioned in a cylindrical casing or barrel so that the expansion of the same about the 10 spindle forming its central point of support is eliminated; there being a frictional and subsequently positive limitation to the contact of the spring against the walls forming the side of this casing or barrel. It is 15 evident that this limitation due to the frictional resistance and, operating against the expansion of the spring cuts down the efficiency of the spring to an appreciable extent.

It is particularly the purpose of this invention to provide for a novel form of casing or support associated with the spring element for driving the clock mechanism whereby the driving spring will have 20 unlimited non-frictional play so that the period of sustenance and driving time of the spring will be increased materially and practically to the extent of twofold.

It is the purpose of this invention particularly to eliminate the use of a casing which 30 usually is in the form of a cylinder either open at the top and covered by the blackplate of the clock, or completely enclosed cylinder, and to substitute therefor, a simple plate or 35 section of a plate having an offset support at one extremity to support one end or extremity of the driving spring, whereby the spring will have free play as to its expansion and whereby no limitation may be imposed upon 40 its contraction or expansive movement due to contact, frictional or otherwise against any walls.

In general, it is aimed to provide an 45 angular plate having apertures therein for the reception of a spindle, disposed centrally at the base portion thereof, which spindle has attached thereto to one extremity of a driving spring, while the other aperture positioned on the other section of the plate 50 and forming an off set angle bar is adapted to maintain the other extremity of the driving spring in fixed relationship so that the rotation of the spindle within the aperture of the base of the plate will allow for the 55 winding and unwinding from the complete

compression to the complete expansion of the spring.

Among the objects of the invention it is aimed to provide a novel form of support associated with the driving spring of a clock 60 whereby considerable freedom of movement for expansion or compression of the said driving spring is permitted; to provide for a novel form of supporting element in the form of an angle bar co-operating with a 65 spindle for supporting and controlling the movement of the spring; to provide a rotating support having one angular projection thereon attachable to one end of a driving spring whereby the spring may be wound 70 about a stationary spindle to complete compression and which spring when being unwound upon actuation of the driving means in the clock will not be restrained in expansion by frictional or pressure contact; to pro- 75 vide a novel form of support for a driving spring which support allows for ease of insertion and removal of the driving spring therefrom; and finally to provide a simple structure for supporting the driving spring 80 whereby the cost of production of the same and the amount of material composing the same are materially reduced in quantum, while at the same time a two-fold increased efficiency of the spring contained therein is 85 provided.

These and other advantages, capabilities, and features of the invention will appear from the subjunct detail description of one specific embodiment therefor illustrated in 90 the accompanying drawings, in which

Figure 1 is a side elevation of a clock forming the subject matter of this invention.

Figure 2 is a section along lines 2—2 of Figure 1.

Figure 3 is an isometric view of the subject matter of this invention.

Figure 4 is an isometric view of a modified form of the invention including the co-operating parts.

Referring more particularly to the reference characters of the drawing, numeral 1, represents the back plate of a clock which back plate is supported in co-operating relation with the front plates 2 and 3 by means 105 of pillar series 4 and 5 on respective sides about the periphery of the clock. In the front portion of the clock there is supported a dial and the casing therefore, of which 6 represents the casing, and 7 represents the 110

well known form of crystal associated with the casing.

The gears and the driving mechanism for the clock being old, no description will be made of the same, in combination with the subject matter of the invention except where it concerns the particular spring driving mechanism.

Referring to Figures 2, 3 and 4 the back plate has supported thereon the casing member 8, consisting of a flat disk 9 having a right angular projection 10 thereof. This right angular projection 10 has formed therein, an aperture 11 and the base portion, 15 9 has formed therein an aperture 12. Through the aperture 12 of the base portion there is adapted to pass a fixedly positioned spindle 13, which spindle is fixed to one of the central plates in the clock, not numbered. The base member 8 has fastened thereto a pawl 15 and a gear or ratchet 17, which gear or ratchet 17 has attached thereto at its extremity a key 18. An extension from the gear in the form of a collar 14 20 passes through an aperture 12 of the base member 9 which collar is fixed directly to the base by means of a riveting operation, whereby the casing member 8 is rotated by the movement of the key. The pawl member 15 is actuated by the spring 16 whereby the pawl is always in contact with a gear 17 which rotates about the back plate 1, and which gear rotates directly with the casing member 8 to the disk portion 9 of which it 25 is riveted by means of the collar 14.

Referring to Figures 2, 3, and 4 the spring member 19 is attachable at one extremity thereof to the angular projection 10, by means of the bolt member 20 which bolt member passes through the aperture 11 of the projection, and the said spring member is attachable at its other extremity by passing around the spindle 13 in the form of a loop 21, one portion of the loop which 30 is fixed to the spindle member by means of a pin 22. In this manner the rotation of the casing member 8 upon actuation of the gear member 17 fixed thereto will cause the extremity of the spring fastened to the projection 10 to rotate about the axis of the spindle 13 and consequently to become compressed thereabout, as the key 18 rotates against the tension of the pawl 15.

In Figure 4 there is shown a modification of the angle plate for supporting the spring, in that the right angular strip 23 is adapted to be fixed directly to the collar 14 of the gear member 17 passing through the aperture in the back plate member 1. The spindle is as in the other figures fixedly supported on one of the center plates in the clock. The right angular strip 23 to which

one extremity of the spring 19 is attached is adapted to rotate upon actuation thereof by means of the key 18 rotating the gear 17 65 which is fixed to said angle strip 23 by means of the collar. The spring at its other extremity is likewise attached by a pin extending from the spindle 13 and penetrating into the loop at that extremity. In this 70 manner the spring member 19 is not restrained as far as lateral expansion is concerned within the confines of the angle bar 23 and upon being compressed through the rotating of the gear 17 and consequently the 75 angle bar member 23 fixed thereto, will be capable of expansion to a considerable degree without having a positive frictional contact with any adjacent wall of the rotating or supporting member, such as is 80 common in the conventional form of spring barrel.

This elimination of the ordinary form of casing or barrel provides for an increase in the length of time of operation of the driven 85 mechanism of the clock from eight to fifteen days which will obviously increase the efficiency of a clock. At the same time there occurs a considerable decrease in the production cost due to the elimination of considerable metal and to the simplicity of the 90 novel form of structural support which will be capable of application to serve as a spring support for varying types of clocks.

It is obvious that various changes and 95 modifications may be made to the details of construction without departing from the general spirit of the invention as set forth in the appended claims.

What is claimed:

1. In a device of the class described, the combination with a driving spring, of an angle bar for supporting the spring, said angle bar being adapted on one face to support the spring and at its opposite face to 105 have fixedly attached thereto one extremity of the spring, a spindle for maintaining the other extremity of the spring in fixed relation and means for rotating said angle bar to compress the spring.

2. A support for driving spring in clocks consisting of an angle bar, one face upon which the spring is adapted to be supported and the other face of which one extremity of the spring is adapted to be attached.

3. A mechanism for clocks consisting of a rotatable angle bar, a spring member supported on one face of said angle bar and having one extremity thereof fixed to the other face of said angle bar, means for fixedly supporting the other extremity of said spring, and means for rotating said angle bar to compress the spring.
